UNITED STATES PATENT OFFICE.

EDWIN FORREST, OF NEW YORK, N. Y.

DESIGN FOR A COMBINED PHONOGRAPH CASE AND CABINET.

55,159.

Specification for Design.

Patented May 18, 1920.

Application filed December 7, 1917. Serial No. 206,108. Term of patent 3½ years.

To all whom it may concern:

Be it known that I, EDWIN FORREST, a citizen of the United States, residing at New York city, in the county of New York and State of New York, have invented a new, original, and ornamental Design for a Combined Phonograph Case and Cabinet, of which the following is a specification, reference being had to the accompanying drawing, forming part thereof.

The figure is a front elevation of a combined phonograph case and cabinet showing my new design.

I claim:

The ornamental design for a combined phonograph case and cabinet substantially as shown.

EDWIN FORREST.
